(57) **CLAIM**

The ornamental design for a vehicle mirror, as shown and described.

DESCRIPTION

FIG. 1 is a top and front perspective view of the first embodiment of a vehicle mirror, showing our new design; FIG. 2 is a top and rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The second embodiment of the vehicle mirror is a mirror image of the first embodiment disclosed in FIGS. 1 through 8 and is not shown.
